UNITED STATES PATENT OFFICE.

GEORGE E. SHARPE, OF STEUBENVILLE, OHIO.

DESIGN FOR A HEAT-TUBE FOR FIREPLACE-HEATERS.

60,063.

Specification for Design.

Patented Dec. 20, 1921.

Application filed June 4, 1921. Serial No. 475,114. Term of patent 14 years.

To all whom it may concern:

Be it known that I, GEORGE E. SHARPE, a citizen of the United States of America, residing at Steubenville, in the county of Jefferson and State of Ohio, have invented a new, original, and ornamental Design for a Heat-Tube for Fireplace-Heaters, of which the following is a specification, reference

being had to the accompanying drawing, forming part thereof.

In the drawing, the figure is a front elevation of a heat tube showing my new design.

I claim:

The ornamental design for a heat tube for fireplace heaters, as shown.

GEORGE E. SHARPE. [L.S.]
